In the drawing, Figure 1 is a side elevation of an atomizer showing my new design; and Figure 2 is a cross section of the atomizer on the line 2—2 in Figure 1, with the bulb portion omitted.

The essential feature of the design resides in the shape of the container portion and particularly in the divergent side thereof adjacent to the bulb.

The ornamental design for an atomizer substantially as shown and described.

In testimony whereof I have hereunto signed my name to this specification.
